UNITED STATES PATENT OFFICE

137,299

DESIGN FOR A MOLDED GLASS CANDY CONTAINER

Turney H. Stough, Jeannette, Pa.

Application October 15, 1943, Serial No. 111,376

Term of patent 14 years

To all whom it may concern:

Be it known that I, Turney H. Stough, a citizen of the United States residing at Jeannette, in the county of Westmoreland and State of Pennsylvania, have invented a new, original, and ornamental Design for a Molded Glass Candy Container, of which the following is a specification, reference being had to the accompanying drawing, forming part thereof.

In the drawing:

I claim:

The ornamental design for a molded glass candy container, as shown.

TURNEY H. STOUGH.
